BAG OPENING AND FILLING MACHINE

Howard G. Allen, North Tonawanda, N. Y., assignor to Consolidated Packaging Machinery Corporation, Buffalo, N. Y., a corporation of New York

Application November 4, 1938, Serial No. 238,771

18 Claims. (Cl. 226—59)

My present invention relates to a bag-opening device.

The invention is particularly concerned with the provision of a bag-opening device which is adapted to open and shape paper bags of any of the well-known types. The invention further contemplates the provision of means for filling a bag after the same has been opened and shaped. Particular advantage is derived by my invention in that it is not limited to any particular type of paper bag and in that it will open and shape paper bags of types which have heretofore been limited to hand-opening and shaping.

In the packaging of granular or pulverulent materials, such as sugar, coffee, cocoa or flour, it is highly desirable to employ a paper bag for reasons of economy. From a merchandising standpoint, commodities must be packaged in an attractive and easily handled manner. For this reason, the economies effected by paper bags have been foregone in many instances because of the desirability of an attractive package. With this problem in mind, certain types of paper bags have been designed with preformed bottoms which may be easily squared and shaped. Certain bags have been so designed that the mere insertion of material or the insertion of an air blast therein will square and shape the bottom. Bags of this type include those bags which are commonly referred to as "automatic," "ABC," self-opening," "satchel bottom" or "diamond fold."

Other types of bags do not lend themselves to such easy opening and shaping because the bottoms thereof are not preformed. Many bags of these types are particularly desirable from the standpoints of cost and efficiency in respect to siftproof characteristics. Certain commodities have been loosely packed in such bags and in some instances have been inserted in such bags by automatic machinery. The packages thus produced are not well shaped and the bottoms thereof are not squared but such shortcomings are not of importance from the standpoint of merchandising of many commodities. If sugar, coffee or similar commodities are to be packaged in bags of these types, the bottoms must be squared in order that the resultant package will be capable of standing on its own bottom and in order that the merchandising requirements shall be met.

One particular form of bag of the type discussed in the preceding paragraph is commonly known as the "square bag." This bag consists of a gusseted flattened tube cut to desired size. The bottom of this bag is closed by the simple

operation of folding one end upon itself and pasting the folded end to an outer wall of the bag body. In some instances, score lines may be formed in proper spaced relation to the closed end to assist in the definition of a square bottom, but such score lines do not serve to preform or otherwise establish an easily squared bottom. In order to meet merchandising requirements in the packaging of sugar, coffee and the like, the square bag must be opened and its bottom must be completely squared by deliberate manipulation prior to the introduction of the commodity therein.

Other forms of bags whose bottoms are not preformed and which must therefore be opened and squared prior to filling include those whose bottoms are closed by stitching and/or tape and which may or may not have gussets formed therein as well as non-gusseted envelopes of various types.

It is an object of the present invention to provide a machine which will open and shape bags of any of the types discussed above.

It is a further object of the present invention to provide a machine which will open and square the bottoms of bags of those types whose bottoms must be squared prior to filling.

It is a further object of this invention to provide means for automatically filling bags which have been opened in accordance with the objects above stated.

Other and further objects of this invention will become more apparent from a consideration of the following description of a preferred but not necessarily the only form of the invention taken in connection with the drawings accompanying and forming a part of this specification.

In the drawings:

Fig. 1 is a front elevation of a machine constructed according to the present invention;

Fig. 2 is an enlarged detail view of a part of the machine shown in Fig. 1 with the valve-box cover removed;

Fig. 3 is a section along the line 3—3 of Fig. 2;

Fig. 4 is a section along the line 4—4 of Fig. 2;

Fig. 5 is a section along the line 5—5 of Fig. 3;

Fig. 6 is a section along the line 6—6 of Fig. 2 showing the bag-opening carriage in its operated position and with a square bag in position thereon;

Fig. 7 is a section along the line 7—7 of Fig. 6;

Fig. 8 is a section along the line 8—8 of Fig. 7;

Fig. 9 is a section along the line 9—9 of Fig. 6;

Fig. 10 is a section along the line 10—10 of Fig. 4;

Fig. 11 is a section along the line 11-11 of Fig. 9 with the opened bag in section to expose the opening fingers to view;

Fig. 12 is a detailed elevation of a rear hinge member having a rear-opening finger attached thereto;

Fig. 13 is a section along the line 13-13 of Fig. 9;

Fig. 14 is a section along the line 14-14 of Fig. 13;

Fig. 15 is a section along the line 15-15 of Fig. 2, and for clarity of illustration the hopper 11 has been omitted and the spout 51 has been sectioned below the plane of line 15-15;

Fig. 16 is a rear elevation of the valve box and supporting means therefor taken in the plane indicated by line 16-16 of Fig. 15;

Fig. 17 is a section along the line 17-17 of Fig. 15;

Fig. 18 is a section along the line 18-18 of Fig. 15;

Fig. 19 is a section along the line 19-19 of Fig. 15;

Fig. 20 is an enlarged view similar to Fig. 16 and showing valve ports and valve seat passageways in dotted lines;

Figs. 21, 22, 23, 25, 26 and 27 are diagrammatic views showing the operation of my device in opening and shaping a square bag; and

Fig. 24 is a section along the line 24-24 in Fig. 27.

Each of the sectional views above identified has been taken in the direction indicated by the arrows accompanying the respective section lines.

Similar characters of reference indicate similar parts throughout the several views.

Referring now to the drawings, there is shown a machine constructed according to my invention. In general, this machine comprises a pedestal or standard 10 upon which is supported a filling hopper 11 and a bag opening device indicated generally at 12. A magazine 13 is provided to hold a supply of bags 14 in a position accessible to the operator. A continuously driven conveyor 15 is supported with the magazine 13 upon a frame supported by the pedestal 10 and additional pedestals 16 and 17. A motor 18 is supported upon the frame and serves to drive the conveyor 15 as well as other parts of the machine to be more particularly described hereinafter. The frame further supports adjustable bag guides 19 and 20 which serve to guide filled bags in their travel upon the conveyor 15.

The opening mechanism is preferably cyclically operated by fluid pressure under the control of the motor 18. To this end, the motor 18 drives, through a belt 21 and pulley 22, a shaft 23 which enters a gear or reduction box 24' containing suitable gearing for driving the conveyor 15 and a shaft 24 at a desirable speed. The shaft 24 is supported in a suitable bearing 25 upon the frame and carries a sprocket 26 which through a suitable sprocket chain 27 and sprocket wheel 28 imparts rotation to a shaft 29 supported in a convenient manner upon the bag opener frame upon pedestal 10. The shaft 29 enters a valve box 30 to operate suitable valves therein for the cyclic operation of the opening mechanism to be hereinafter described.

A sprocket 31 is mounted for rotatable adjustment upon shaft 29 and may be secured in adjusted position as by a set screw 31'. The sprocket 31, through a sprocket chain 32 and sprocket wheel 33, drives a cam shaft 34 sup-

ported above the filling hopper 11. The cam shaft 34 controls the weighing and dumping mechanism within a battery of automatic weighing and dumping devices 35 supported above the hopper 11. The weighing devices 35 are supplied with the commodity to be packaged by individual spouts 36 leading from a suitable source of supply. The material to be packaged is conducted by gravity or otherwise through the spouts 36 to the automatic weighing devices 35 which are arranged to operate in definite order under the influence of the cam shaft 34. As shown in the drawings, there are four weighing devices 35 which operate successively in order to give ample time for accurate weighing of successive charges of material to be packaged. The details of the weighing and dumping apparatus form no part of the present invention and it is to be noted that any such apparatus may be used wherein the dumping operation may be accurately controlled. For the purposes of the present invention it is sufficient that the weighing devices shall furnish weighed charges of material to the hopper 11 in definite timed relationship with the operation of the bag-opening device in order that a charge of material may be introduced into a bag immediately that the same has been opened and shaped to receive such material.

30 The cyclic rate of operation of the bag opening device and of the weighing and filling devices may be varied by changing the speed of the motor 18 or by variation in gear ratios within the gear box 24'.

35 In the operation of the device thus generally described, a bag 37 is transferred from the stack 14 to a suitable gripping device forming a part of the bag opener. The transfer of the bag from the stack 14 to the bag opener may conveniently be manually effected. However, it is to be distinctly understood that such transfer may be made by suitable automatic devices. The gripping device holds the bag in position while the opening device opens and squares the bottom of the bag 37. When opening and squaring is complete, a charge of material is placed into the bag by the filling device. Immediately thereafter, the bag is released by the gripping device and dropped upon the conveyor 15 which, together with the guides 19 and 20, conducts the filled bag 37' to a delivery point.

40 The device thus generally described operates in fixed cycles and it is necessary that the empty bags shall be placed in position upon the opening device at a particular portion of the cycle. Occasional failures to thus properly position the bag must be expected and, accordingly, the conveyor 15 is preferably constructed of open material such as coarse flexible wire mesh through which material discharged by the weighing device may pass to a spillage bin 38 located directly beneath the discharge opening of the filling device.

45 60 65 70 75 For convenience in manual manipulation, the bag magazine 13 may comprise a trough-like body having a generally vertical front wall. A shelf 39 may be provided in such a position as to support the stacks of bags 14 in an inclined relationship against the vertical front wall of the magazine. The upper edges of the bags will thus be offset relative to one another in order that the uppermost bag may be conveniently separated and removed from the stack.

A detailed description of the bag opening and

squaring device will now be given. Referring first to Figs. 15 and 16, there is shown a spaced pair of clamp blocks 40 which may be conveniently clamped to the standard 10 by U-bolts 41 which pass through suitable recesses or openings in the clamps 40 and through angles 42 and 43 respectively. The opening and squaring device of the present invention is supported upon the angles 42 and 43. The construction thus described provides a firm and steady support and at the same time provides for vertical adjustment of the device relative to the standard 10. Such vertical adjustment may be availed of to accommodate the device to be hereinafter described for operation upon bags of various sizes and types.

The angles 42 and 43 serve through suitable supporting means to support the valve box 30 and the bag opening device 12. It will be understood that the hopper 11 and weighing devices 35 shown in Fig. 1 are supported by the standard 10 by suitable means not shown.

The bag opening device 12 comprises in general a set of four angular fingers suitably interconnected with operating means to contract to a collapsed condition in which they define rectangular planes of dimensions less than the rectangular dimensions of a bag when fully opened and may be easily introduced into a bag and to expand to such position as to define rectangular planes substantially equal in all dimensions to the rectangular outline of an opened paper bag. These fingers are supported for vertical motion whereby they may be projected in their collapsed condition into the interior of a bag and then expanded to bag-shaping position.

A complementary pair of angles 44 and 45 are suitably interconnected by members 46 and 47 which form parts of cylinder heads to be hereinafter described and a spacer or top covering member 48 to form a stationary frame upon which the principal elements of the bag-opening device are supported. This frame is supported in a vertical position by the angles 42 and 43 as shown in Fig. 2. The cover or spacing member 48 has suitably attached thereto or formed integrally therewith a downwardly extending channel-shaped extension comprising a rear wall 49 and side walls 50. The walls 49 and 50 may conveniently fit in telescoped relation upon the side walls of angles 44 and 45 and serve therewith to form a generally rectangular enclosure for certain of the operating parts to be described.

At its lower end, the wall 49 has secured thereto by suitable means, such as rivets and spacing members, a spout 51. The spout 51 (see Fig. 3) is designed to form a continuation of the hopper 11 and to this end is supported in telescoping relationship with the lowermost end of the hopper 11.

As seen in Fig. 6, the spout 51 is of generally tapered conformation and diminishes in cross-section toward the lowermost end thereof. By reference to Fig. 9 it will be seen that the spout 51 is provided with angular indentations 52 formed in its rear corners and extending through the major portion of the length of the spout. These indentations are of sufficient depth to accommodate the thickness of the bag opening fingers in order that the fingers and the rear wall 53 of the spout may form a generally plane or flush surface when the fingers are collapsed and in their uppermost position as shown in Fig. 4. By the construction thus defined there is provided a tapered spout of suitable length and di-

mensions supported in fixed relationship with the bag opening frame and designed for cooperation with the bag opening fingers.

The front bag opening fingers 54, 55 are mounted for swinging movement in a single vertical plane and to this end are secured at their upper ends to a pair of hinge members 58 and 59 respectively. The hinge members 58 and 59 are complementary but are otherwise identical and hence a detailed description of one of these members will suffice.

Referring now to Fig. 4, it will be seen that the hinge member 58 includes a vertical web portion 60 in which are formed suitable apertures for reception of fastening means such as screws 61 which secure the finger 54 to the hinge member 58. The web 60 has formed thereon a lip 62 (Fig. 10) which serves as a seat for the angular corner of finger 54. A boss 63 is formed integrally with or otherwise secured to the outer face of the web 60 and serves to receive a bearing stud 64. The stud 64 has a reduced portion 65 passing through a mounting plate 66 and is secured to the mounting plate as by a nut or cap screw 67. The boss 63 abuts the mounting plate 66 and is held upon the stud 64 by a suitable retaining collar 68 (Fig. 4). The structure thus described provides for rocking movement of the hinge 58 and finger 54 about the stud 64 as an axis. A stud 69 (Fig. 13), similar to the stud 64, is provided as an axis for the hinge member 59 and finger 55 is mounted at the opposite end of plate 66. These two studs are parallel and hence the front fingers 54 and 55 may be rocked toward and away from one another in a vertical plane parallel to the plane of the section upon which Fig. 13 is taken.

As shown in Figs. 13 and 14, the front fingers 54 and 55 are interconnected by an angularly disposed link 70 pivoted at its ends to suitable pivot mountings 71 and 72 provided respectively upon the fingers 54 and 55. The angularity of the link 70 and the disposition of its pivots relative to the studs 64 and 69 are such as to cause all angular movements of the fingers 54 and 55 about their axes 64 and 69 to be equal in extent and opposite in direction.

As seen in Figs. 4 and 6, each of the hinge members 58 and 59 has rearwardly and downwardly projecting extensions 73 and 74. Each of these extensions carries a boss, one of which is indicated at 75 in Figs. 4 and 10 and the other at 76 in Fig. 11. These bosses are adapted to receive stub shafts 77 and 78 formed upon hinge members 79 and 80 which are provided for support of the rear fingers 56 and 57 respectively. As particularly shown in Fig. 10, the boss 75 is confined between the body of the hinge and a retaining cap or ring 81 secured as by a cap screw 82 to the stub shaft 77. The axis of rotation of stub shaft 77 is disposed at approximately a right angle to the axis of rotation of the hinge 58 about the stud 64 and these two axes are located generally within the same horizontal plane. As a result, the hinge 79 rocks with hinge 58 about the stud 64 and, in addition, the hinge 79 may rock about its own axis 77 relative to the hinge 58. Thus, the rear fingers 56 and 57 are mounted to rock in a vertical plane generally parallel to the plane in which the front fingers 54 and 55 rock and, in addition, are mounted for independent rocking motion in a plane generally normal to the plane of fingers 54 and 55. A brief reference to Figs. 21 to 23 and 25 to 27 will disclose that the front fingers 54 and 55 rock only

about pivots 64 and 64' while the rear fingers 56 and 57 rock about the pivots 77 and 78 as well as about the pivots 64 and 64'.

It will be understood that the rear hinge members 79 and 80 are identical throughout except that they constitute a complementary pair. Each of the hinge members 79 and 80 is connected to its respective bag-opening finger 56 or 57 as by screws 83 passing through a web portion 34 of the hinge and threadably received in the finger. Each of the hinge members is further provided with a finger-seating lip 85 similar to the lip 62 provided upon the front hinge members 54 and 55.

The fingers 54, 55 and 56, 57 are spring urged into their collapsed position as illustrated in Fig. 4. To this end, the hinge member 58 is provided with an upwardly extending, perforated ear 86 and the hinge member 59 is provided with a similar ear 87. The perforations in the ears 86 and 87 are tapped to threadably receive set screws 88 and 89 respectively which are provided with suitable lock nuts 90 and 91 (Figs. 9 and 13). A rod 92 is provided with reduced end portions which are loosely positioned in the perforations of the ears 86 and 87. Mounted upon the rod 92 is a pair of spacing collars 93 and an expansible spring 94. The spring 94, acting through collars 93, tends to spread the upper ends of the hinges 58 and 59 apart and thus to swing the lower portions of the front-opening fingers 54 and 55 toward one another about the studs 64 and 69. The set screws 88 and 89 constitute adjustable stops to limit the swinging movement of the fingers in the opposite direction under the influence of means which will be hereinafter described. To this end, the screws 88 and 89 may be adjusted to abut the ends of rod 92 at various angular positions of the fingers.

As explained above, the rear fingers 56 and 57 swing toward and away from each other with the front fingers 54 and 55. The spring 94, therefore, influences the rear fingers along with the front. It is considered advisable to provide an additional expansible spring 95 (Figs. 9 and 11) carried by a rod 96 whose ends are loosely received by sockets 97 and 98 mounted respectively upon the rear hinges 79 and 80. The ends of the spring 95 bear upon the sockets 97 and 98 and the expansive force of the spring 95 serves to assist the spring 94 in urging both sets of fingers into collapsed position.

Contractile springs 99, 100 (Figs. 6 and 9) are anchored respectively to the rear hinges 79 and 80 and to a relatively fixed part of the bag opening frame. The springs 99 and 100 tend to rock the rear hinges 79 and 80 about the stub shafts 77 and 78 to swing the rear fingers inwardly toward the spout 51.

The springs 94, 95 and 99, 100 tend to swing the rear fingers 56 and 57 into a position wherein they will closely nest with the inwardly sloping rear corners of the spout 51 and the indentations 52 formed in the rear wall 53 of the spout. The springs 94 and 95 tend to swing the front fingers 54 and 55 into a position wherein they will closely nest with the substantially vertical front corners of the spout 51. In Fig. 15, the spout 51 has been sectioned in a horizontal plane substantially below the plane of the line 15-15 in Fig. 2 in order to illustrate the nested position of the fingers and spout when the fingers are collapsed and the bag-opening carriage is in its uppermost position. When the fingers are thus collapsed, the fingers and the spout 51 form a substantially

smooth, tapered body which may be readily inserted into the mouth of a bag.

According to the present invention, suitable power actuated means is provided to rock the bag-opening fingers about their respective axes against the force of the springs 94, 95, 99 and 100 into a position wherein the fingers form a generally rectangular, skeleton-like form of shape and size conforming to the interior shape and size of a bag with which the device is to be used. In the embodiment shown in the drawings, the power means is actuated by a fluid pressure medium such as compressed air although it is to be understood that any suitable fluid pressure medium may be used or that suitable electrical or mechanical power actuated means may be substituted for the fluid pressure actuated means herein disclosed.

As shown in Fig. 15, there are provided two fluid pressure motors 101 and 102 of the cylinder and piston type. These motors are connected by tubes 103 and 104 and a suitable fitting 105 to a tube 106 which is connected with the valve box 30. The valve mechanism within box 30 is so designed as to alternately direct air under pressure to the motors 101 and 102 and to allow the air in the motors to exhaust as will be explained in detail hereinafter.

In Fig. 6 the motor 102 is shown in section and it comprises a clamp ring 107 in which a cylinder 108 is seated, a cylinder head 109 and a piston 110. The cylinder body is confined between the clamp ring 107 and the cylinder head 109 by bolts or cap screws 111 passing through external portions of the head 109 and threadably received in the clamp ring 107 (Fig. 9). The piston is provided with a flexible packing cup 112 held thereon as by a washer 113 and cap screw 114. The head 109 is provided with a port 115 adapted to receive a suitable fitting 116 for connection with the tube 104. Air is admitted to and exhausted from the interior of the cylinder through the port 115.

The clamp ring 107 has lateral extensions 117 loosely connected as by pins 118 (Fig. 9) to a pair of rearwardly extending links 118 and 119 pivotally connected at their forward ends, as at 120 and 121, to suitable bifurcated ears 122 and 123 formed upon the front hinge members 58 and 59 respectively. The links 118 and 119 serve to hold the motor 102 in proper lateral position relative to the bag-opening device and the loosely pivoted construction provides the necessary freedom of movement of the front hinges 58 and 59.

The motor 102 is supported in a vertical direction by an angle 124 (Fig. 6) secured as by cap screws 125 to the clamp ring 107 and to a cross bar 126 (Figs. 6 and 11). The cross bar 126 is pivotally supported at its ends upon trunnions 127 formed upon the rearward extensions 13 and 14 of front hinge members 58 and 59. The cross bar 126 may be held upon the trunnions 127 by any suitable means such as cotter pins 128 (Fig. 10). The trunnions 127 are so placed upon their respective hinge extensions that their axes form a continuation of the axes of studs 64 and 69 about which the hinge members 58 and 59 are adapted to swing. Thus, the cross bar 126 forms a substantially stationary support for the motor 102 and, furthermore, serves to tie the rearward extensions of the front hinges together for greater steadiness and uniformity of operation.

The piston 110 has formed thereon a bifurcated portion 129 extending outwardly from the cylinder (Figs. 6 and 9) and drilled to receive a

pin 130. A horizontally disposed push rod 131 is received within the bifurcation and is pivotally connected to the piston by the pin 130. The rear hinge members 79 and 80 have formed thereon bifurcated rearward extensions 132 which receive rollers 133 rotatably mounted upon pins 134 carried by the extensions 132 (see Fig. 12). The rollers 133 are held against the push rod 131 by the springs 99, 100. When air is admitted to the motor 102 the piston 110 is driven to the right as viewed in Figs. 4, 6 and 9 and the push rod 131 bears against the rollers 133 to rock the rear fingers 56 and 57 about their pivots 77, 78 to move the fingers from the position in Fig. 4 to the position in Figs. 6 and 9. The pivotal mounting of push rod 131 acts to equalize the pressure exerted upon the fingers and to insure uniformity of operation. The anti-friction rollers 133 are provided to permit free swinging of the hinge members 58, 59 and 79, 80 about their 20 stud shafts 77 and 78 by means which will hereinafter be described.

Adjustable stops are provided to accurately limit expansive movement of the rear fingers 56 and 57 under the influence of the fluid pressure motor 102. These stops may comprise screws 135 (Figs. 4 and 9) threaded through upward extensions 136 formed upon the front hinge members 58 and 59. The rearward ends of screws 135 extend into positions to be abutted by the upper portions of the rear hinge members 79 and 80. Suitable lock nuts 137 may be provided to hold the screws 135 in proper adjusted position.

The fluid pressure motor 101 may be identical with the motor 102 and detailed description thereof will be omitted. The clamp ring 138 of the motor 101 has extensions 139 formed thereon which extensions are drilled to receive draw rods 140 and 141 which act as the sole support for the motor 101. The rod 140 extends through enlarged openings 142 formed in each of the front hinge members 58 and 59 (Figs. 4 and 6) and extends outwardly beyond the opposite side of the bag-opening carriage (Fig. 9). The rod 141 extends through enlarged, horizontally extending slots 143 formed in each of the rear hinges 79 and 80 (Figs. 4 and 6) and extends outwardly beyond the opposite side of the bag-opening carriage (Fig. 9). The outwardly extending ends of the rods 140 and 141 extend through a draw bar 144 held on the rods as by nuts or caps 145 secured to the ends of rods 140 and 141.

The piston of motor 101 has a bifurcated extension 146 to which is pivotally attached, as by a pin 147, a push bar 148 drilled adjacent its ends for sliding reception of the rods 140 and 141 (Fig. 9). The push bar 148 is adapted to bear against a stud 149 extending laterally from the front hinge member 58 and an antifriction roller 150 rotatably mounted in a bifurcated lateral extension 151 of the rear hinge member 79 (see Fig. 12).

The draw bar 144 is adapted to bear against a stud 152 and roller 153 carried respectively by the front hinge 59 and rear hinge 80 and respectively similar to the stud 149 and roller 150 above described. The draw rods 140 and 141 extend through the clamp ring extensions 139 and have stop and lock nuts 154 thereon to hold the clamp ring in position upon the rods.

When air is admitted to the motor 101, the piston causes the push bar 148 to rock the hinge members 58 and 79 about the stud 64 toward the position illustrated in Fig. 11. The body of the motor 101 exerts an equal and simultaneous force

against the stop nuts 154 and the draw rods 140 and 141 whereby the draw bar 144 is caused to rock the hinge members 59 and 80 about their pivot 69 toward the position illustrated in Fig. 11. The ultimate position of the hinge members and fingers carried thereby under the influence of motor 101 is adjustably limited by abutment of cross rod 92 with screws 88 and 89 as above described.

The loose engagement of rod 140 with the apertures 142 in the front hinges and the loose engagement of the rod 141 in the slots 143 in the rear hinges are provided to prevent binding due to relative angular movement between the hinge members and the draw rods. The slots 143 allow swinging movement of the rear hinges transversely of the draw rod 141. The pivotal connection 147 between the piston of motor 101 and the push bar 148 allows movement of various parts without danger of binding. The antifriction rollers 133 and 150 act as thrust members for cooperation with their respective push bars 131 and 148, and, at the same time, facilitate the relatively transverse movement between the rear hinge members and thrust bars which occurs as a result of the bi-planar swinging movement of the rear hinge members.

In Figs. 2, 4 and 6 there is shown a bag-holding device which is particularly adapted for use with the bag opener herein disclosed. This device includes a pair of spaced temporary holding rollers 155 (Figs. 2 and 4) and a power actuated gripping jaw 156 (Figs. 2 and 6) which cooperate with a gripping plate 157 for holding a bag in position. The bag-holding device is supported at a level somewhat above the lower end of spout 51 in order that the mouth of a bag may be introduced over the spout and held by the holding device in position for opening, shaping and filling as shown in Figs. 2, 4 and 6.

As shown in Fig. 4, an angle 158 is supported between angles 44 and 45 and has a downwardly projecting portion 159 which carries a spacing block 160 to which the clamping plate 157 is attached. The spacing block 160 has mounted therein a horizontally disposed shaft 161 on the outer ends of which are mounted two-armed levers 162 which carry the rollers 155 at their lower ends and whose upper ends are attached to suitable springs 163 which urge the rollers 155 into contact with the clamping plate 157. As shown in Fig. 4, a bag 37 may be partially opened and its mouth placed over the spout 51. One wall of the bag may be conducted over the face of plate 157 and the upper edge or lip of this wall may be easily forced between the plate 157 and the spring pressed rollers 155. The tension of springs 163 is so chosen as to hold an empty bag in position but to be ineffective to hold a filled bag.

Referring now to Fig. 4, it will be seen that the shaft 161 also carries a pair (Fig. 2) of bell crank levers 164 working in slots in the projection 159. The lower arms of the bell cranks 164 carry a cross shaft 165 on which the clamping jaw 156 is pivotally carried. The other, substantially horizontal arms of bell cranks 164 are pivotally connected as at 166 to a piston 167 of a fluid pressure motor 168 similar in essential features to the motors 101 and 102 described above. The motor 168 may be conveniently supported within the angle 158 and is provided with a port 169 through which the motor may be supplied with air under pressure and through which the motor may exhaust. The port 169 has therein a suitable fitting 170 to which is connected a tube 171

leading to valve mechanism within valve box 30. A tension spring 172 is stretched between the piston pin 166 and a suitable anchorage 173 on the motor body. The spring 172 serves to return the piston 167, bell cranks 164 and clamp 156 to open or non-clamping position when the air is permitted to exhaust from motor 168.

The clamp 156 serves to firmly hold a bag 37 in position while it is being opened, shaped and filled and is of such strength as to securely hold a filled bag. Thus, an empty bag may be positioned upon the bag-holding device and held temporarily by the rollers 155. After a suitable interval of time, air is admitted to the motor 168 which rocks the bell crank 164 in a clockwise direction as seen in Fig. 4 to set the clamp 156. The clamp 156 holds the bag during the opening, shaping and filling operation and, when filling is complete, the valve mechanism in valve box 30 allows the air in motor 168 to exhaust and spring 172 releases the clamp 156. Since the force of temporary holding rollers 155 is insufficient to hold a filled bag, the same will drop from the holding device to the conveyor 15.

The bag opening and shaping means, comprising the opening fingers 54, 55, 56 and 57 and the operating means therefor, is mounted for vertical movement from a position in which the fingers are collapsed and nested with the spout 51, as shown in Fig. 4, to a position wherein the lower tips of the fingers are in a position to square the bottom of a bag 37 supported by the holding devices 155, 156 as shown in Fig. 6. To this end the mounting plate 66 is attached as by cap screws 114 (Fig. 6) and a suitable spacing member 175 to the lower end of a channel 176. The channel 176 serves as a carriage member and may be seen in section in Fig. 9 and in side elevation in Fig. 3. The channel 176 carries a plurality of sets of track rollers 177 on each side thereof as seen in Figs. 3 and 9. The rollers 177 are mounted upon suitable bearings 178 secured to V-shaped supporting blocks 179 which are in turn secured as by screws 180 to the sides of the channel 176. The rollers 177 ride upon a pair of tracks 181 carried respectively by the angles 44 and 45. The tracks 181 may conveniently be square in cross section and may be secured through spaced V blocks 182 and screws 183 to their respective angles 44 and 45. The channel 176 and the bag opening device supported thereby constitute a bag opening carriage which is thus mounted for vertical movement accurately guided by the antifriction rollers 177 and tracks 181.

Suitable power actuated means may be provided to effect the vertical movements of the bag-opening carriage. It is preferred to use fluid pressure actuated power means and in the embodiment shown in the accompanying drawings a double acting air motor of the cylinder and piston type is employed. It will be understood that any suitable mechanical or electrical power means may be employed for this purpose and that the present invention is not limited to the use of an air motor.

In Figs. 1 or 2 the carriage air motor is indicated generally by the reference numeral 184. The motor 184 comprises a lower head 185, shown in detail in Figs. 7 and 8, an upper head 186, shown in detail in Figs. 3 and 5, a cylinder 187, a piston 188, shown in detail in Fig. 6, and a piston rod 189. The piston rod 189 is connected at its upper end to the upper end of the carriage channel 176. As shown in Figs. 2 and 3, the up-

per end of the piston rod 189 is fitted with an eye 190 which receives the reduced end of a cylindrical stud 191 secured to the upper end of the channel 176. The stud 191 may be formed with a flange 192 and a reduced threaded portion 193 passing through the channel 176 and adapted to receive a nut 194 which serves to secure the stud in proper position.

The piston 188 is secured to the piston rod 189 and comprises upper and lower oppositely disposed flexible cups 195 and 196 respectively. The upper portion of the piston 188 has formed thereon a shoulder 197 while the lower portion has a similar shoulder 198. Extending upwardly beyond the shoulder 197 there is a reduced portion terminating in a plunger 199 while a similar plunger 200 is formed on a reduced portion extending downwardly from the lower shoulder 198. The shoulders and plungers serve purposes which will be hereinafter more clearly brought out.

The lower and upper cylinder heads 185 and 186 include the portions 46 and 47 above described which serve the dual purpose of securing the cylinder heads to the angles 44 and 45 and of spacing the angles 44 and 45. The lower head 185 and upper head 186 are provided with seats 201 and 202 respectively (Figs. 8 and 3) adapted to receive the opposite ends of the cylinder 187. The heads and cylinder are held in assembled relation by a suitable number of elongated bolts 203 extending through the heads and adapted to draw the heads toward one another into firm seating engagement with the ends of the cylinder 187. The upper head 186 is formed with an extension 204 (Fig. 3) through which the piston rod 189 may extend. A packing nut 205 having suitable packing material 206 therein is threaded upon the extension 204 and serves to prevent escape of air around the piston rod 189. The double-ended piston 188 divides the air motor into lower and upper chambers having separate cylinder heads through which air may be supplied and exhausted.

Except for the packing gland 204, 205, 206 above described and minor details to be herein-after described the cylinder heads 185 and 186 constitute a complementary pair and a detailed description of one of these heads will suffice. Referring now to Figs. 6, 7 and 8, it will be seen that the head 185 comprises two separate parts, a lower part 207 and an upper part 208. This particular construction is adopted in order to simplify casting, machining, and assembling of the head. The upper part 208 has extending completely therethrough an opening concentric with the cylinder seat 201 and a bushing 209 is positioned in this opening. The internal diameter of the bushing 209 is such as to snugly receive the plunger 200 of the piston 188 and is extended beyond the head part 208 to cooperate with the shoulder 198 of the piston 188 to establish a definite stop or final position of the piston relative to the cylinder 185. The lower part 207 has formed therein a recess 210 which opens into the bushing 209 and which through a slot 211, recess 212 and passageway 213 communicates with a main air chamber 214. The recess 210 serves as an inlet and exhaust port and the rate of flow therethrough may be controlled by a needle valve 215 whose point may be adjusted toward and away from the intersection of the passageway 213 and chamber 214 and which may be locked in air-tight adjusted position by a lock nut 216 adapted to bear upon a packing washer 217.

The portion of the upper part 208 which lies within the cylinder 187 but outside of the bushing 209 has formed therein an inlet and exhaust port 218 communicating with a mating recess 219 formed in the lower part 207 and a passage-way 220 opening into the main air chamber 214. An adjustable needle valve 221 similar to valve 215 may be provided to control the flow of air through the port 218.

In the portion of the upper part 208 in which the port 218 is formed there is also formed a pair of inlet ports 222 communicating through a slot 223 in the upper part 208 and an opening 224 formed in the lower part 207 with the main air chamber 214. A ball check valve 225 is mounted in the upper part 208 and is urged by its spring 226 to seat in the opening 224 to prevent exhaust of the cylinder through the ports 222.

The main air chamber 214 is open at one end to receive a suitable fitting 227 which is connected as by a tube 228 to the valve box 30.

The upper cylinder head 186 is shown in Figs. 3 and 5 and it will be noted that parts thereof have been indicated by reference numerals bearing a prime and corresponding to the numerals applied to corresponding parts of the lower head 185. The inlet and exhaust port 210' differs in dimensions and design from the port 210 of head 185 to compensate for the passage of the piston rod 189 therethrough. The main air chamber 214' of the upper head is connected by a fitting 227' and the tube 228' to the valve box 30.

The valve mechanism in box 30 is arranged to alternate the inlet and exhaust of each of heads 185 and 186 and further to alternate the cycles of inlet and exhaust between the two heads. Thus, either the lower or upper cylinder chamber may have fluid pressure admitted thereto while the other chamber is allowed to exhaust whereby the piston 188 is caused to move upwardly or downwardly within the cylinder 187.

The cylinder heads 185 and 186 above described are designed to produce a uniform, rapid stroke of the piston and to provide a cushioned stop at each end of the travel of the piston. Referring again to Figs. 6, 7 and 8, the operation of the lower cylinder head will be described. Air under pressure is admitted from the valve box 30 to the chamber 214 and passes through the openings 213, 220 and 224 to the ports 210, 218 and 222 respectively. The air passing through port 210 acts directly upon the head of plunger 200 while the air passing through ports 218 and 222 acts directly upon the piston cup 196. Thus, air under pressure is immediately applied to substantially the entire area of the piston 188 to effect rapid movement thereof. When the plunger 200 leaves bushing 209, the lower cylinder chamber is supplied with air emerging from all of the ports 210, 218 and 222 and the stroke of the piston continues. During this time, the upper cylinder head 186 is exhausting and will provide a cushioned stop for the end of the piston stroke. Since the action of the upper head is identical with that of the lower head the exhausting operation will be explained in connection with the more detailed showing of the lower head.

It will be understood that exhausting of the lower head 185 will occur when pressure is supplied to the upper head 186 to produce a downward movement of the piston 188 as from the position shown in Fig. 3 to that shown in Figs. 6 or 8. During the major portion of the stroke, the air within the lower cylinder chamber exhausts through ports 210 and 218. Since the

ball check valve prevents exhaust through ports 222, the air within the exhausting chamber will be somewhat compressed and will thus assure a uniform and controlled rate of piston travel.

5 When the plunger 200 enters the bushing 209, the port 210 is closed and the air within the main cylinder chamber may exhaust only through the port 218. Proper adjustment of the needle valve 221 will restrict the exhaust through port 218 and so cushion the end of the stroke as to afford a gentle final stop between the shoulder 198 and bushing 209.

From the above detailed description it will be apparent that there is provided a particularly desirable carriage moving device. The needle valve adjustments may be availed of to adapt the device for raising and lowering the carriage at optimum speed and with a minimum of shock irrespective of wide variations in fluid pressure which may be encountered in different plants.

In Figs. 15 to 20 inclusive, there is shown a particular valve arrangement which may conveniently be used to control the fluid pressure motors of the bag opening device above described. It will be understood that any valve arrangement suitable for the purpose may be used and that the following detailed description is for illustrative purposes only. As shown in Figs. 15 and 16, the tubes 106, 171, 228 and 228' lead from their respective air motors to a valve seat 229 forming a part of the valve box 30. As shown in Fig. 20 and in Figs. 17, 18 and 19, the valve seat 229 has formed therein suitable passageways and recesses for cooperation with the ports of valves seated thereon. A passageway 230 is formed in the valve seat 229 and constitutes the main passageway through which a fluid pressure medium is supplied to the valves. As shown in Fig. 20, the passageway 230 is open at one end to receive a suitable fitting or pipe 239 connected with an air compressor or other suitable source of fluid pressure not shown.

Fig. 17 is a sectional view of a valve 231, actuating mechanism therefor and the valve seat 229, showing an arrangement suitable for control of the bag clamp motor 168. The valve 231 comprises a body mounted upon the valve seat 229 and which has suitable chambers therein and openings between the chambers controlled by poppets 232 and 233. The pressure passageway 239 is connected by recess 234 and inlet valve port 235 to the valve chamber 236. Referring now to Fig. 15, it will be seen that the tube 171 leading from motor 168 is connected as by suitable pipe fittings 237 to the valve seat 229. Referring back to Fig. 17, it will be seen that the motor 168 is thus connected by a passageway 238 in the valve seat and an outlet valve port 239 with a valve chamber 240. A valve chamber 241 opens through an exhaust valve port 242, recess 243 and exhaust opening 244 to the atmosphere. The poppet 232 is urged to closed position by an expansion spring 245 extending between a packing washer 246 and a tappet 247. The poppet 233 is similarly urged to closed position and is provided with a tappet 248. The tappets 247 and 248 may be alternately depressed to open the valves 232 and 233 by a rocker 249 pivoted at 250 upon the valve body. The rocker is urged by a spring 251, superior to the spring 245, to rock in a clockwise direction, as seen in Fig. 17, whereby the poppet valve 232 is normally maintained in an open position. The spring 251 is fastened at one end to the upper arm of rocker 249 and at its other end the spring is anchored as to a pin 252 lying outside the valve

seat 229. The lower arm of the rocker 249 is provided with an antifriction roller 253 which is adapted to cooperate with a suitable cam mechanism to rock the rocker 249 in a counterclockwise direction whereby the poppet 232 is allowed to close and the poppet 233 is opened.

In the position illustrated in Fig. 17 the poppet 232 is closed and the fluid pressure supply from passageway 230 is closed off within chamber 236. Poppet 233 is open to allow the motor 168 to exhaust through chambers 240 and 241 and exhaust opening 244 to the atmosphere. In the position thus illustrated the bag clamp 156 (Fig. 2) is in open position corresponding to the position of parts illustrated in Figs. 1, 2 and 4. When the cam mechanism allows spring 251 to rock the rocker 249 to open poppet 232 and close poppet 233 the fluid pressure medium flows from passageway 230 through chambers 236 and 240, outlet port 239, etc., to the motor 168 whereby the clamp 156 is moved to clamping position illustrated in Fig. 6.

A valve 254, identical with valve 231 above described, may be provided for control of the motors 101 and 102 which effect expansion and contraction of the bag-opening fingers. As shown in Figs. 15 and 20 the valve 254 is seated upon the valve seat 229 and is provided with an inlet port 255 communicating with supply passageway 230, an exhaust port 256 and an outlet port 257 connected by a fitting 258 with tube 106 leading to the motors 101 and 102. The valve 254 is urged by spring 259 into an exhaust position as described above in connection with valve 231 whereby the bag opening fingers remain normally collapsed as shown in Fig. 4. Cam mechanism is provided to reverse the valve 254 to cause expansion of the fingers to the position shown in Fig. 6.

The upward and downward movements of the bag-opening carriage may be controlled by a valve 260 similar in general design to the valves above described. The valve 260 is provided with four ports and four poppets. Fig. 18 is a section in the plane of one pair of ports and poppets while Fig. 19 is a section in the plane of the other pair of ports and poppets. In Fig. 19 there is shown an inlet port 261 communicating through a recess 262 with the supply passageway 230 and opening into an inlet chamber 263 in the valve body. The chamber 263 projects forwardly from the plane of Fig. 19 through a passageway 264 into the plane of Fig. 18 and into an inlet chamber 265.

In the plane of Fig. 19 the valve 260 is provided with an outlet chamber 266 and outlet port 267 communicating through a recess 268, passageway 269 and a fitting 270 with the tube 228 (Fig. 16) leading to the lower cylinder head 185.

In the plane of Fig. 18 the valve 260 is provided with an outlet chamber 271 and outlet port 272 communicating through a recess 273, passageway 274 and a fitting 275 with the tube 228' leading to the upper cylinder head 186.

In the plane of Fig. 18 the valve 260 is provided with an exhaust chamber 276 which extends through a passageway 277 rearwardly from the plane of Fig. 18 into the plane of Fig. 19 and into an exhaust chamber 278. The chamber 278 has a portion 279 which extends forwardly into the plane of Fig. 18. As shown in Fig. 18 the portion 279 communicates through a passageway 280 with an exhaust port 281 which opens through a recess 282 and exhaust opening 283 to the atmosphere.

The valve 260 is provided with upper poppets 284 (Fig. 19) and 285 (Fig. 18) and lower poppets 286 (Fig. 19) and 287 (Fig. 18). These poppets

are similar in all respects with the poppets described above in connection with Fig. 17. In the valve position illustrated in Figs. 18 and 19, the upper poppets 284 and 285 are held open by the action of a spring 288 upon the upper arm of a rocker 289 bridging the tappets. The valve may be reversed by cam mechanism acting upon an antifriction roller 290 carried by the lower arm of rocker 289.

10 In the valve position illustrated in Figs. 18 and 19 a fluid pressure medium from supply passageway 230 enters the chamber 263 (Fig. 19) passes through the open poppet 284 to outlet chamber 266 and thus to the lower cylinder head 185 to produce an upward movement of the bag-opening carriage. Pressure medium exhausted from the upper cylinder head 186 passes through outlet port 272 (Fig. 18) into chamber 271 through open poppet 285 into the exhaust chamber 276 and passage 277 (Fig. 18) to chamber 278 and 279 (Fig. 19), through 279 (Fig. 18) into passageway 280 and exhaust port 281 and thus to the atmosphere.

When the valve 260 is reversed, pressure medium flows from supply passageway 230 to chamber 263 (Fig. 19) through passageway 264 into chamber 265 (Fig. 18) through the now open poppet 287 into outlet chamber 271 and through port 272 to the upper cylinder head 186 to produce a downward movement of the bag-opening carriage. Pressure medium exhausted from the lower cylinder head 185 passes through outlet port 267 (Fig. 19) into chamber 266 and through the now open poppet 286 into exhaust chamber 278, 279 and thus through port 281 (Fig. 18) to the atmosphere.

As shown in Fig. 15, the valves 231, 254 and 260 may be mounted upon the valve seat 229 in proper alignment for operation by a set of individually adjustable cams carried by the cam shaft 29. The shaft 29 is rotatably carried in bearings 291 and 292 secured to the valve box 30 and is rotated by the motor 18 as described above in connection with Fig. 1.

45 The cam provided for operation of the bag clamp valve 231 may comprise two relatively adjustable segments 293 and 293' (Figs. 15 and 17) secured to hubs 294 and 294'. The hubs 294 and 294' may be fixed in adjusted angular relation to the shaft 29 by any suitable means such as set screws (not shown). The segments 293 and 293' may be further secured in adjusted position relative to one another as by a clamp bolt 295 passing through arcuate slots 296 and 296' formed respectively in the segments 293 and 293'.

50 The cam provided for operation of the bag-opening finger valve 254 comprises segments 297 and 297' (Figs. 15 and 17) mounted as are the segments 293 and 293' upon the shaft 29. Arcuate slots 298 and 298' and a clamp bolt 299 are provided to assist in securing the segments in adjusted relationship.

55 The cam provided for operation of the carriage valve 260 comprises relatively adjustable segments 300 and 300' (shown in Figs. 15 and 18 and omitted from Fig. 17 for purposes of clarity) mounted as are the segments 293 and 293' upon the shaft 29. Arcuate slots 301 and 301' and a clamp bolt 302 are provided to assist in securing the segments in adjusted relationship.

The valve positions in Figs. 15, 17, 18 and 19 correspond to the machine position illustrated in Figs. 1, 2, 3 and 4 in which the carriage is up.

5 fingers 54-57 are collapsed and the clamp 156 is open. It will be assumed that an empty bag 37 has been positioned beneath temporary holding rollers 155 as shown for example in Fig. 4. Accordingly, the cam 293, 293' is positioned to hold the valve 231 in the position shown in Fig. 17 and the cam 297, 297' is positioned to hold the valve 254 in the position shown in Fig. 17. The cam 300, 300' is positioned away from follower 290 whereby the valve 260 is held in the position illustrated in Fig. 18 by the spring 288. The cams 293, 297, 300 are adjusted relatively to one another upon the shaft 29 in order to operate their respective valves in proper timed relation and the individual segments of these cams are adjusted to vary the duration of operation of each valve. A preferred adjustment of the cams is illustrated in Figs. 17 and 18 of the drawings and the resultant sequence of machine operations will now be described.

10 The shaft 29 is rotated in a clockwise direction as indicated by the arrows and the cam segment 293' will be withdrawn from follower 253 allowing the spring 251 to reverse valve 231. The reversal of valve 231 operates as above described to set the bag clamp 156. Continued rotation of shaft 29 will project the cam segment 300' into contact with the follower 290 and result in reversal of the carriage valve 260. The reversal of valve 260 operates as above described to start the downward movement of the bag-opening carriage. Continued rotation of shaft 29 will withdraw the cam segment 297' from its follower and result in reversal of the finger controlling valve 254 which operates as above described to cause expansion of the bag-opening fingers 54-57. Preferably, the cams 300' and 297' are so timed that the fingers 54-57 are fully expanded shortly before the downward movement of the carriage is complete. When the carriage reaches its lowermost position and the fingers are fully expanded a charge of material is dumped from one of the weighing devices 35 (Fig. 1) under timed control of the cam shaft 34. The material starts to flow through hopper 11 and spout 51 into the now fully opened and shaped bag 37. While the filling operation proceeds the cam segment 297 is approaching its follower and when filling is well started the segment 297 reverses the valve 254 to collapse the fingers 54-57. Shortly thereafter the segment 300 is withdrawn from the follower 290, whereby the valve 260 is reversed to start the upward travel of the carriage. The filling operation continues while the carriage is returned to its uppermost position and continues thereafter until completed. Upon completion of the filling operation the segment 293 contacts the follower 253, reverses valve 231 and thus releases the bag clamp 156. The segments 293, 293' are so adjusted as to provide a sufficient period of time for the filled bag to drop upon conveyor 15 and to allow the operator of the machine to position an empty bag for the initiation of a new cycle of operation identical with that just described.

15 It will be readily apparent that the cams 293, 297 and 300 may be variously adjusted and timed to compensate for variations in the time required for flow of material from the weighing devices to the bag as well as to compensate for varying degrees of skill in the placement of empty bags in position where manual operation is contemplated. Thus, when a freely flowing material is to be packaged it may be possible to shorten the portion of the cycle assigned to the filling operation, lengthen the portion assigned to positioning of

the bag and increase the cyclic rate of operation. When an automatic bag-positioning device is used in connection with the device of the present disclosure, it would perhaps be possible to shorten that portion of the cycle assigned to bag positioning and lengthen the time available for opening and filling whereby the cyclic rate of operation could be materially increased.

20 While the individual adjustments of cams 293, 297 and 300 are relative to the shaft 29 and are, therefore, relative to sprocket 31, it will be apparent that by adjustment of the sprocket 31 relative to the shaft 29 the timing of the filling device may be conveniently varied without disturbance of the cams.

25 The operation of the bag-opening device will now be described in connection with the opening of a square bag. Referring now to Figs. 21 and 25, it will be seen that a square bag 37 has been partially opened, placed over the lower ends of the fingers 54-57 and positioned beneath the rollers 155. The lower portion of the bag body tapers to a bottom fold or crease 303 formed during manufacture and a rectangular bottom may be defined therein by score lines 304 and 305 formed in the front and rear walls and in the gusseted side walls respectively. As explained above in the description of the cyclic operation of the device, the clamp 156 is set and the collapsed fingers 54-57 start their downward movement. While the fingers may remain collapsed until downward travel is complete and be thereafter expanded to bag-opening position, it is preferred to overlap these operations. Accordingly, from a position in the general vicinity of that illustrated in Figs. 22 and 26, the further downward movement of the fingers 54-57 may be accompanied by rocking thereof about the pivots 64, 64', 77 and 78.

30 The length of fingers 54-57 and the extent of vertical movement thereof are so proportioned with regard to the particular bag to be opened that in their lowermost position the lower tips of the fingers lie within a plane substantially coincident with the plane of score lines 304, 305, or, stated otherwise, in a position wherein only sufficient bag material lies beyond the ends of the fingers to provide a rectangular bottom of dimensions substantially equal to the rectangular dimensions of the bag body when fully expanded or opened. Thus, while the following description is made in connection with a bag provided with score lines 304 and 305, it will be understood that the operation of the fingers is in no way dependent upon the provision of such score lines. The fingers are preferably formed with substantially right angular outer corners and the extent of their expansive movement is preferably so limited that in their fully expanded position the lower tips thereof define a rectangle substantially congruent with the rectangular bag bottom defined by score lines 304 and 305. Thus, in the movement of the fingers from the position in Figs. 22 and 26 to the position in Figs. 23, 27 and 28 the corners of the bag bottom will be positively moved away from each other in paths which are resultantly diagonal and the score lines 304, 305 will be positively moved to positions wherein they establish a rectangular bottom of desired dimensions.

35 The fold or crease 303 will be flattened out and drawn upwardly substantially into the plane of score lines 304 and 305. Detailed sectional views of the opened and squared bag are presented in Figs. 6 and 11. In this connection, it may be

noted that in Fig. 11 the bag 37 is sectioned along a vertical plane substantially including the bottom crease 303.

As shown in Fig. 24, the fingers 54-57 are formed as angles whose legs substantially lie within and establish the planes in which the vertical walls of the bag 37 lie when the same is fully opened and shaped. This, together with advantages of lightness and added strength, is of decided value and the construction thus disclosed is preferred but it is to be understood that the fingers 54-57 may be variously constructed as, for example, the cross-sections thereof may be rectangular, circular or otherwise.

The present device is particularly adapted for opening and squaring the bottoms of square bags and, accordingly, the foregoing description has been presented in connection with such bags. While this is an important feature of the present invention, it is also of importance that the device disclosed is equally capable of opening and squaring any of the ordinarily available commercial forms of bags or envelopes irrespective of bottom formation or closure.

While for the purpose of complying with statutory requirements the above detailed description of a preferred form of the present invention has been set forth, it is to be understood that such description is to be interpreted in an illustrative rather than in a limiting sense. Modifications and variations may be resorted to within the scope of the appended claims.

I claim:

1. In a bag opening, squaring and filling device; the combination of a bag filling means, a plurality of fingers adapted for insertion into a bag, means to hold an empty bag in position to receive said fingers, said means being incapable of holding a filled bag, additional means operable to engage said bag and hold the same while it is being opened and filled, means operable in timed relation with the operation of said additional means to move said fingers into said bag, means operable in timed relation with the movement of said fingers into said bag to move said fingers in two directions substantially transverse to the direction of movement of said fingers into said bag whereby to bring said bag to predetermined rectangular shape and size, means operable in timed relation to the movements of said fingers to cause said bag filling means to fill said bag, means operable in timed relation with the operation of said filling means to cause withdrawal of said fingers from said bag, and means operable in timed relation with the operation of said filling means to cause said additional bag holding means to release its engagement with said bag.

2. In a device for opening and squaring the bottom of a bag, the combination comprising a set of four relatively movable fingers, means to move said fingers into a position in which the ends thereof are positioned at the corners of a rectangle having smaller dimensions than the corresponding dimensions of the rectangle formed by the bottom of said bag when fully squared whereby said fingers may be inserted into said bag, means to move said fingers into said bag to such an extent that only sufficient bag material will lie beyond the ends of said fingers to provide a rectangular bottom with dimensions substantially equal to the cross-sectional dimensions of the body of said bag when fully opened, and means for moving the fingers so that the ends thereof will be positioned at the

corners of said bag and to expand each dimension of the original rectangle formed by the fingers until each dimension equals the corresponding dimension of the rectangle formed by the bottom of said bag when fully squared whereby to draw the bag material beyond the ends of said fingers into a rectangular form lying substantially within the plane of the ends of said fingers.

3. In a device for opening and filling bags, the combination of a filling spout adapted for reception within a bag to be opened and filled, a plurality of fingers, means to move said fingers into a position in which the ends thereof are positioned at the corners of a rectangle having smaller dimensions than the corresponding dimensions of the rectangle formed by the opened bag whereby said fingers may be received within said bag, means to hold a bag in a partially open position around said spout and said fingers, means to move said fingers into said bag to such an extent that only sufficient bag material will lie beyond the ends of said fingers to provide a rectangular bottom with dimensions substantially equal to the cross-sectional dimensions of the body of the bag when fully opened, and means for moving the fingers so that the ends thereof will be positioned at the corners of said bag and to expand each dimension of the original rectangle formed by the fingers until each dimension equals the corresponding dimension of the rectangle formed by the bottom of said bag when fully opened.

4. In a device for opening bags, the combination of a set of four relatively movable fingers, means to move said fingers into a position in which the ends thereof are positioned at the corners of the rectangle having smaller dimensions than the corresponding dimensions of the rectangle formed by the opened bag whereby said fingers may be inserted into said bag, means to hold a bag in a partially open position around said fingers, means to move said fingers into the body of said bag to such an extent that only sufficient bag material will lie beyond the ends of said fingers to provide a rectangular bottom with dimensions substantially equal to the cross-sectional dimensions of the body of said bag when fully opened, and means for moving the fingers so that the ends thereof will be positioned at the corners of said bag and to expand each dimension of the original rectangle formed by the fingers until each dimension equals the corresponding dimension of the rectangle formed by the bottom of said bag when fully squared whereby to draw the bag material beyond the ends of said fingers into a rectangular form lying substantially within the plane of the ends of said fingers.

5. In a device for opening and filling bags, the combination of a filling spout adapted for reception within a bag to be opened and filled, a set of four relatively movable fingers of such length that when inserted into said bag only sufficient bag material will lie beyond the ends thereof to provide a rectangular bottom with dimensions substantially equal to the cross-sectional dimensions of the body of said bag when fully opened, means to move said fingers into a position in which the ends thereof are positioned at the corners of the rectangle having smaller dimensions than the corresponding dimensions of the rectangle formed by the bag when opened whereby said fingers may be received within said bag, means to hold a bag in a

partially open position around said spout and said fingers, and means for moving the fingers so that the ends thereof will be positioned at the corners of said bag and to expand each dimension of the original rectangle formed by the fingers until each dimension equals the corresponding dimension of the rectangle formed by the bottom of said bag when fully opened.

6. In a device for opening and filling bags, the combination of a filling spout adapted for reception within a bag to be opened and filled, means to supply said spout with predetermined charges of bag filling material, a set of four relatively movable fingers of such length that when inserted into said bag only sufficient bag material will lie beyond the ends of said fingers to provide a rectangular bottom with dimensions substantially equal to the cross-sectional dimensions of the body of said bag when fully opened, means to move said fingers into a position in which the ends thereof are positioned at the corners of the rectangle having smaller dimensions than the corresponding dimensions of the rectangle formed by the opened bag whereby said fingers may be received within said bag, means to hold a bag in a partially open position around said spout and said fingers, means for moving the fingers so that the ends thereof will be positioned at the corners of said bag and to expand each dimension of the original rectangle formed by the fingers until each dimension equals the corresponding dimension of the rectangle formed by the bottom of said bag when fully opened, and means to cause operation of said material-supplying means to deliver a predetermined charge of bag-filling material to said bag after the same has been fully opened.

7. In a bag opening and filling device the combination of a main frame, a filling spout mounted upon said frame, said spout being adapted to enter the mouth of a bag, a carriage mounted for vertical movement upon said frame, a plurality of bag opening members mounted upon said carriage and adapted for insertion into the mouth of said bag when said carriage is in its upper position, bag holding means mounted upon said frame and adapted to hold said bag with said spout and members positioned in the mouth thereof, means to lower said carriage to insert said members into the body of said bag, means to move said members to spread said bag to predetermined rectangular shape and size, means to deliver a predetermined charge of bag filling material through said spout to the interior of said bag after the same has thus been spread, means operable during the filling of said bag for collapsing said members from their spread position, means to move said carriage to return said collapsed members to their upper position prior to completion of filling of said bag, and means for releasing said holding means upon the completion of the filling of said bag.

8. In a bag opening and filling device, the combination of a main frame, a filling spout mounted upon said frame and sized for entering the bag, a carriage mounted for vertical movement upon said frame, a plurality of bag opening members surrounding said spout and mounted upon said carriage for movement therewith, said fingers being movable relative to said carriage and occupying a collapsed position in close proximity to said spout when said carriage is in its uppermost position, a clamp mounted upon said frame, means for moving said clamp into engagement with said bag while said spout and members

are positioned in the mouth thereof, fluid pressure means to lower said carriage to insert said members into the body of said bag, fluid pressure means to move said members to spread said bag to predetermined rectangular shape and size, means to deliver a predetermined charge of bag filling material through said spout into said bag after said bag has thus been spread, means operable during the filling of said bag for collapsing said members from their spread position, fluid pressure means to return said carriage and members to their upper position prior to completion of the filling of said bag, and means for moving said clamp out of engagement with said bag upon the completion of the filling of said bag.

9. In a device of the class described the combination of members insertible into a bag for opening said bag and means for filling said bag, a gripper adapted to support an empty bag in predetermined operative position relative to said opening members and filling means, said gripper being incapable of supporting said bag when filled, a second gripper adapted to engage and hold said bag while the same is being opened and filled, and means operating in timed relation with the operation of said opening and filling means to cause said second gripper to engage and hold said bag while the same is being opened and filled and to release said bag when opening and filling thereof has been completed.

10. In a device of the class described, a plurality of fingers insertible into the corners of a bag and normally defining a rectangle having smaller dimensions than the corresponding dimensions of the rectangle formed by the bottom of said bag when fully squared, means to hold said bag in position to receive said fingers, said fingers being of such length that when inserted into said bag only sufficient bag material will lie beyond the ends of said fingers to provide a rectangular bottom with dimensions substantially equal to the cross-sectional dimensions of the body of said bag when fully opened, means for projecting said fingers into said bag, means for moving the fingers so that the ends thereof will be positioned at the corners of said bag and to expand each dimension of the original rectangle formed by the fingers until each dimension equals the corresponding dimension of the rectangle formed by the bottom of said bag when fully opened to positively spread said bag to predetermined rectangular shape and size, means for filling said bag, means for withdrawing said fingers from said bag, means to release said bag from said bag-holding means, and a control device adapted to initiate operation of said several means in the sequence above set forth.

11. In a device of the class described, a plurality of fingers insertible into the corners of a bag and normally defining a rectangle having smaller dimensions than the corresponding dimensions of the rectangle formed by the bottom of said bag when fully squared, said fingers being of such length that when inserted into said bag only sufficient bag material will lie beyond the ends of said fingers to provide a rectangular bottom with dimensions substantially equal to the cross-sectional dimensions of the body of said bag when fully squared, a gripping device to hold said bag in position to receive said fingers, means to move said gripping device to gripping position, means for projecting said fingers into said bag, means for moving the fingers so that

the ends thereof will be positioned at the corners of said bag and to expand each dimension of the original rectangle formed by the fingers until each dimension equals the corresponding dimension of the rectangle formed by the bottom of said bag when fully squared to positively spread said bag to predetermined rectangular shape and size, means for filling said bag, means for returning said fingers from their spread position, means for withdrawing said fingers from the bag, means to move said gripping device to bag releasing position, and a control device adapted to cause operation of said several means in the sequence above set forth.

12. In a device of the class described, a plurality of fingers insertible into the corners of a bag and normally defining a rectangle having smaller dimensions than the corresponding dimensions of the rectangle formed by the bottom of said bag when fully squared, said fingers being of such length that when inserted into said bag only sufficient bag material will lie beyond the ends of said fingers to provide a rectangular bottom with dimensions substantially equal to the cross-sectional dimensions of the body of said bag when fully squared, means to hold an empty bag in position to receive said fingers, said means being incapable of holding a filled bag, additional means to hold said bag in position, said additional means being capable of supporting the bag during opening and filling, means for projecting said fingers into a bag, means for moving the fingers so that the ends thereof will be positioned at the corners of said bag and to expand each dimension of the original rectangle formed by the fingers until each dimension equals the corresponding dimension of the rectangle formed by the bottom of said bag when fully squared to positively spread said bag to predetermined rectangular shape and size, means for filling said bag, means for withdrawing said fingers from said bag, means to release said additional bag-holding means, and a control device adapted to cause operation of said several means in the sequence above set forth.

13. In a device of the class described: a plurality of members insertible into a bag; means to hold a bag in position to receive said members; means for projecting said members into said bag; means for moving said members in such manner as to spread said bag to predetermined rectangular shape and size; means for filling said bag; means for returning said members from their spread position; means for withdrawing said members from said bag; means to release said bag-holding means; a control device adapted to initiate operation of said several means in the sequence above recited; conveying means below said bag for removing the same; and means temporarily to hold said bag in position to receive said members prior to the operation of said first-named holding means, said last-named holding means being incapable of supporting said bag when filled.

14. In a device of the class described: a plurality of members insertible into a bag; means to hold a bag in position to receive said members; means for projecting said members into said bag; means for moving said members in such manner as to spread said bag to predetermined rectangular shape and size; means for filling said bag; means for returning said members from their spread position; means for withdrawing said

members from said bag; means to release said bag-holding means; a control device adapted to initiate operation of said several means in the sequence above recited; conveying means below said bag for removing the same; and means temporarily to hold said bag in position to receive said members prior to the operation of said first-named holding means.

15. In a device of the class described the combination with members insertible into a bag for opening said bag, means for filling said bag and a conveyor: a constantly operative gripper adapted to support an empty bag in predetermined operative position relative to said opening members and filling means and said conveyor, said gripper being incapable of supporting said bag when filled; a second gripper adapted to engage and hold said bag while the same is being opened and filled; and means operating in timed relation with the operation of said opening and filling means to cause said second gripper to engage and hold said bag while the same is being opened and filled and to release said bag when opening and filling thereof has been completed whereby said bag may gravitate upon said conveyor.

16. In a device of the class described, a plurality of fingers insertible into the corners of a bag and normally defining a rectangle having smaller dimensions than the corresponding dimensions of the rectangle formed by the bottom of said bag when fully squared, fluid pressure responsive means to engage and hold a bag in position to receive said fingers, said fingers being of such length that when inserted into said bag only sufficient bag material will lie beyond the ends of said fingers to provide a rectangular bottom with dimensions substantially equal to the cross-sectional dimensions of the body of said bag when fully opened, fluid pressure responsive means for projecting said fingers into said bag, fluid pressure responsive means for moving the fingers so that the ends thereof will be positioned at the corners of said bag and to expand each dimension of the original rectangle formed by the fingers until each dimension equals the corresponding dimension of the rectangle formed by the bottom of said bag when fully opened to positively spread said bag to predetermined rectangular shape and size, means for filling said bag, fluid pressure responsive means for withdrawing said fingers from said bag, fluid pressure responsive means to release said bag from said bag-holding means, and a control device including a plurality of valves connected with said fluid pressure responsive means and adapted to initiate operation of said several means in the sequence above set forth.

17. In a device of the class described, a plurality of fingers insertible into the corners of a bag and normally defining a rectangle having smaller dimensions than the corresponding dimensions of the rectangle formed by the bottom of said bag when fully squared, fluid pressure responsive means to engage and hold a bag in position to receive said fingers, said fingers being of such length that when inserted into said bag only sufficient bag material will lie beyond the ends of said fingers to provide a rectangular bottom with dimensions substantially equal to the cross-sectional dimensions of the body of said bag when fully opened, fluid pressure responsive means for projecting said fingers into said bag, fluid pressure responsive means for moving the fingers so that the ends thereof will be positioned at the corners of said bag and to expand

each dimension of the original rectangle formed by the fingers until each dimension equals the corresponding dimension of the rectangle formed by the bottom of said bag when fully opened to positively spread said bag to predetermined rectangular shape and size, means for filling said bag, fluid pressure responsive means for withdrawing said fingers from said bag, fluid pressure responsive means to release said bag from said bag-holding means, and a fluid pressure responsive control device adapted to cause operation of said several means and including a plurality of individually adjustable rotatable cams whereby the time of operation of each of said several means relative to the time of operation of each of the other of said means may be varied.

18. In a machine for opening and squaring the bottom of a bag, a pair of relatively movable fingers, a second pair of fingers respectively and movably carried by said first-mentioned fingers, all of said fingers being of such length that when inserted into said bag only sufficient bag material will lie beyond the ends of said fingers to provide a rectangular bottom with dimensions substan-

tially equal to the cross-sectional dimensions of the body of said bag when fully opened, means to move all of said fingers into a position in which the ends thereof are positioned at the corners of a rectangle having smaller dimensions than the corresponding dimensions of a rectangle formed by the bottom of said bag when fully squared whereby said fingers may be inserted into said bag, means for projecting said fingers into said bag, and means for imparting a movement of separation to said first-mentioned and said second-mentioned pairs of fingers and to impart a movement of separation to the first and second fingers of each said pair of fingers whereby the ends of said fingers will be positioned at the corners of said bag and to expand each dimension of the original rectangle formed by said fingers until each dimension equals the corresponding dimension of the rectangle formed by the bottom of said bag when fully squared whereby to draw the bag material beyond the ends of said fingers into a rectangular form lying substantially within the plane of the ends of said fingers.

HOWARD G. ALLEN.
